TEXTILE MACHINE

William J. Elvin, Frostburg, Md., Raymond D. Reel, Keyser, W. Va., and Elmer R. Stahl, Meyersdale, Pa., assignors to Celanese Corporation of America, a corporation of Delaware

Application February 9, 1940, Serial No. 318,028

13 Claims. (Cl. 242—18)

This invention relates to textile machines and relates more particularly to improved devices for producing bobbins and like packages of twisted yarn.

In its broadest aspect the instant invention comprises an improvement in the take-up means of a twisting and winding machine. In twisting and winding devices as heretofore commonly constructed, the twisted yarn was wound upon a bobbin or similar package supported upon a gudgeon by means of a cork covered roll or drum which frictionally rotated the bobbin. As is well known in the art, the use of gudgeons presented many difficulties including manipulation, misalignment, wear and maintenance. Moreover, the cork roll or frame often injured the flanges of the bobbin necessitating extremely high buffing costs, the flange defects also injuring the yarn, thereby reducing the quality thereof. It is, accordingly, an important object of this invention to provide an improved take-up means for a twisting and winding device which will be free from the above mentioned and other disadvantages, and which will be simple, efficient and inexpensive in operation.

Another object of this invention is the provision of a twisting and winding device for producing large packages of yarn which are perfectly wound both as to density and traverse and which are free from all trapping.

Still another object of this invention is to provide improved means for winding yarn on a bobbin whereby damage to the flanges of the bobbin is entirely eliminated.

A further object of this invention is the provision of a twisting and winding device which automatically stops itself at the end of the run, i. e., when the bobbins have a predetermined amount of yarn wound thereon.

Other objects of this invention will appear from the following detailed description.

In the accompanying drawings, wherein the preferred embodiment of our invention is shown,

Fig. 1 is a front view of the device of our invention, only one twisting spindle with its supply package being shown for the sake of clarity.

Fig. 2 is an end elevation of our device,

Fig. 3 is a detail view showing the bobbin mountings and traverse bars, and

Fig. 4 is a wiring diagram showing the electrical hook-up for the device of our invention.

Like reference numerals indicate like parts throughout the several views of the drawings.

Referring to Fig. 1 of the drawings, the reference numeral 5 indicates the framework of an

up-twisting machine of the usual construction in which the twisting spindle 6 is driven by means of an endless belt 7 mounted on a pair of pulleys, one of which (not shown) is driven by a suitable motor 8 (see Fig. 4), the other pulley 9 being an idler. While only one spindle is shown, it is to be understood that a plurality of spindles are normally mounted and driven by the endless belt.

The take-up means in accordance with this invention is of the direct driven type and derives its motor power from the same source as the belt 7 which drives the spindle 6, namely, motor 8 which may be a 7½ H. P., 440 volt 3 phase motor. To this end the idler pulley 9 is fixed to a shaft 10, mounted in bearing 11, which shaft forms the input or ingoing shaft of a speed reducer 12. The output or outgoing shaft 13 of speed reducer 12 drives double sprockets 14 which are connected to double sprockets 15 by means of articulated chain 16. The sprockets 15 are mounted on and drive the input or constant speed shaft 17 of a positive, infinitely variable speed transmission 18, known as a "P. I. V." gear and is manufactured by the Link-Belt Company. Such a gear is shown on page 693 of the Link-Belt Company catalog No. 700 (1937). This variable speed unit 18 is so constructed and arranged that changes in speed may be effected at will and while the same is under load by suitable means provided for this purpose, as will hereinafter be set forth.

The drive for the take-up means is taken from the output or variable speed shaft 19 of the variable speed unit through a spur gear 21 keyed on said output shaft, which cooperates with idler gears 22 and 23 mounted on an adjustable bracket 24, the idler gear 23 meshing with and rotating spur gear 25 which supplies the variable speed drive to the main take-up shaft 26 through double sprockets 27 and 28 connected by an articulated chain 29. The spur gear 21 is used as the twist change gear and may be replaced by a gear of different size where it is desired to change the twist, as is well understood in the art. The main take-up shaft 26 supplies the drive for the individual pairs of take-up devices of the take-up means through a spiral gear 31, mounted on said shaft 26, which cooperates with spiral gear 32 mounted on spindle shaft 32' for rotating spindles 33. It is to be understood that there is a spiral gear 31 and a spiral gear 32 for rotating each pair of spindles. The take-up means of this invention is mounted on an angle iron cross bar 34 extend-

ing across the machine and fixed to the framework thereof.

The variable speed unit 18 is provided with means for controlling or regulating the rate of speed of the output shaft 19. This control of the speed is effected through a control shaft 35 which is operated automatically from said output shaft 19 of the variable speed unit 18 in the following manner. Thus, spur gear 21 on said output shaft cooperates with idler gears 36 and 37 which are carried by adjustable brackets 18 and 39, respectively, and spur gear 41. The spur gear 41 has attached thereto and rotates sprocket 42 which through link chain 43 rotates sprocket 44 mounted on input shaft 45 of a speed reducer generally indicated by the reference numeral 46. On the output shaft 75a of said reducer is sprocket 75 which drives sprocket 76 through a link chain, thus rotating speed control shaft 35 of "P. I. V." unit 18. The spur gear 41 is used as the denier or time change gear and may be replaced by gears of different size, as is well understood in the art.

In accordance with this invention, automatic switching controls are employed during the operation of the device. These switching controls are positively connected to the control shaft 35 through sprocket 48, mounted on said control shaft, which rotates a sprocket 49 through a link chain 51. Fixed to the shaft on which the sprocket 49 is attached is a gear 52 meshing with and rotating the spur gear 53. Rotating integrally with spur gear 53 are switch actuating devices comprising sectional step cam 54 and arms 55 and 56, each of which arms is angularly adjustable. The cam 54 actuates limit switch 57, mounted in control box 57', which controls the starting take-up spindle speed. Arm 55 actuates a limit switch 58, mounted in control box 58', which controls the reversing point at the higher speed needed to remove the "slack or back lash" in the variable speed unit internal gears. An arm 56 is adapted to actuate limit switch 59, mounted in control box 59', which controls the stopping of the machine at the low finishing speed at the end of each run. The operation of the automatic switching controls will hereinafter be described in greater detail.

Means are provided for automatically resetting the take-up spindle speed from the low finishing speed to the high starting speed. The drive for this automatic resetting is furnished by an auxiliary 110 volt reversible motor 61 through sprockets 62 and 63 which are connected by a chain 64. The sprocket 63 rotates a gear 65 which operates a chain of gears comprising gears 66, 67, 68, 69, 71 and 72. The gear 72 meshes with and rotates a gear 73 mounted on the variable speed unit control shaft 35. When the reversible motor 61 operates to rotate control shaft 35 in a counter-clockwise direction, the speed of the output shaft 19 of the variable speed unit is increased, and when the control shaft 35 is rotated clockwise the speed of the output shaft 19 is decreased. These rotational effects are provided by the reversible motor 61 through the gearing connections as given above and a gear 73 and a built-in 2-way clutch 74 mounted on the control shaft 35. The clutch 74 is adapted to release the control shaft from the positive drive from the speed reducer 46 through the medium of sprocket 75 on output shaft 75a of the speed reducer, which output shaft is supported in outboard bearing bracket 75b, and sprocket 76 mounted on control shaft 35, said

sprockets 75 and 76 being connected by chain 71. The positive action of the 2-way clutch 74, which may be either of the types shown or page 550 of the Link-Belt Company catalog above mentioned, and gear 73 is not interfered with by virtue of the disengageability of the compounded gearing arrangement 65-72, said compounded gearing arrangement being mounted on an arm 78 pivotally mounted at 79 and being actuated by interconnected solenoids 81 and 82 through a connecting rod 83 which is spring loaded as shown at 84.

The operation of the traverse arrangement will now be described. The drive for this traverse arrangement is derived from main take-up shaft 26 on which is mounted a sprocket 85 which rotates a sprocket 86 by means of a chain 81. The sprocket 86 is mounted on the input shaft 88 of a speed reducer 89 on the output shaft 91 of which is mounted a sprocket 92 which through chain 93 rotates a sprocket 94, the sprocket 94 being adapted to rotate a pinion gear 94' which in turn effects the rotation of creeper gears 95 and 96 and a groove cam 97. The creeper gear 96 and the grooved cam 97 are mounted on a sleeve 98 and are disposed between a cam 99, mounted on creeper gear 95, and a cam 101 on a shaft 98'. The cams 99 and 101 are adapted to give a lateral or creeping motion to the creeper gear 96 and grooved cam 97 which is transmitted through cam follower 102 fixed to a rod 102a pivotally mounted in bracket 102b fixed to the frame 5 and in a slide 103, sliding on arm or shaft 104 also fixed to the frame 5. A main traverse bar 105 is attached to and is moved to and fro by said slide 103. The main traverse bar 105 transmits the traverse and creeper effect to auxiliary traverse bars 106 through pinions 107, which effects the traversing of the yarn 107' from supply package 108 on to the yarn packages 109 through porcelain thread guides 110.

To put this device in operation at the beginning, or after the doffing period, it being assumed that switches 111 and 112 are closed, the button 113, or "reset" button, is pushed which closes a circuit and thus energizes the latching coil 114 of relay A making contacts *a* and *b* of said relay A. Button 115, or "run" button, is next pushed thus energizing solenoid *m* of relay B which makes contacts *c*' and *c* of said relay B and also causes the circuit of motor 8 to close thus starting up said motor 8 and, since the points *d* are already in contact, also causes the motor 61 to start up and run in counter-clockwise rotation. A transformer 115' is provided to step down the voltage in the line to the 110 volts required for motor 61. The pushing of the run button 115 also closes the circuit to solenoid 81 thus energizing said solenoid which causes rod 83 to be pulled down thereby operatively connecting the gear train 65-72 to gear 73 to drive the speed control shaft 35. The rotation of control shaft 35 operates the spur gear 53 and the switch actuating devices mounted thereon. The arm 55 is so positioned on spur gear 53 that it throws limit switch 58 when the yarn packages 109 have reached a predetermined speed of rotation, which in the present case is 435 R. P. M. The throwing of the limit switch 58 causes the energizing of the "reverse" latching coil 116 of relay C thus breaking the contact *d* and making contact *e* of said relay C thereby energizing solenoid 82 and also causing the field of motor 61 to be reversed to clockwise rotation. This causes the speed

control shaft 35 to reduce the speed of the output shaft 19 of the variable speed unit until the limit control cam 54 which has held contacts *e*—*z* of limit switch 57 closed for an interval, to open thus breaking the circuit of motor 61 and solenoid 82. This stops the motor 61 and disengages the gear train 65—72 from gear 73 and clutching arrangement 74 on the speed reduction control shaft 35 as the take-up package speed reaches a predetermined point, namely 405 R. P. M. in this case. It should be understood that this automatic resetting of the take-up package speed may be accomplished at the end of a run instead of at the beginning of a run as set forth herein. In addition, said resetting may be accomplished at the beginning or at the end of a run by other means.

From this point, which is the initial take-up package speed, the speed of the output shaft 19 is properly decreased by the drive from said shaft 19 through the speed reducing unit 46 to control shaft 35 until, when the take-up package reaches a speed of 257 R. P. M., the arm 56 actuates the limit switch 59 which makes contact through contact *b* of relay A energizes unlatching coils 117 and 118 of relays C and A, respectively, thus breaking contact *e* of relay C and contacts *a* and *b* of relay A. The breaking of contact *a* of relay A to the 110 volt control of the magnetic switch in relay B, governing the motor 8, automatically stops the machine at the end of each run.

The machine may be stopped at any time during the run for yarn inspection or for any other reason by pushing stop button 119 and may be restarted to continue the run by pushing run button 115.

The device of the instant invention produces many advantageous results. For example, full packages of yarn are readily removed from the take-up spindles with no lifting up of heavy packages or encountering the inherent difficulty in removing gudgeons as is necessary on equipment employing friction drums. Empty bobbins slip straight on the take-up spindles and always register in the same place, thus making traverse guide adjustments almost entirely unnecessary. Gudgeon difficulties include manipulation, misalignment and cost of maintenance. These difficulties are entirely eliminated by the present invention giving instead a permanently located take-up spindle which, coordinated with an improved traverse arrangement, gives perfectly wound packages, both as to density and traverse, which are free from all trapping of yarn.

By the use of the device of the instant invention, the expensive item of injuries to the flanges of the bobbins is substantially eliminated. This means not only that the extremely high buffing costs on these bobbins will no longer be an item, but also that these bobbins will last longer and that the yarn wound thereon will not be injured in quality by reason of flange defects caused on the contact driven units by virtue of the hazardous arrangement of the fingers and cork rolls or drums. The actual procedure of doffing and putting ends up is somewhat different but also somewhat superior since the device lends itself ideally to squad doffing, with the machine idle, which is the modern practice. With doffing accomplished, nothing is required of the operative but to push the starting switch button, whereupon the machine automatically changes from finishing spindle speed to a start-ing take-up spindle speed. No attention or sur-

veillance by the operative is necessary after the first few minutes of the run.

Our device stops itself automatically at the end of the run and this is an important feature of the instant invention. Since the device of applicants' invention is entirely automatic and needs no attention during the run, production per operative is greatly increased. Moreover, the machine of the instant invention produces 10 yarn of the highest quality, of uniform length on perfectly traversed ideal unwinding packages. We have found that the final useable quantity 15 of product per spindle on the device of the instant invention is much higher than that of twisting and winding machines heretofore employed. This is due to the fact that the necessity for operatives to clean off at the waste spindle the outer layers of yarn on the full or partly 20 full take-up packages is eliminated. This is not necessary on the device of the instant invention, first, because the outer layers cannot be damaged by running as on the cork rolls and, second, because the bad ends and tails next to the barrel 25 on the spinning bobbin supply packages are not twisted up and run off on to the take-up package but are left on the supply package to be reeled off at high speed later.

We have also found that the device of the instant invention produces packages of yarn having a build and density which is equal to or superior to the large packages of yarn, i. e., those containing 2 pounds or more of yarn, heretofore produced. The twist on the yarn is exceptionally uniform, having a variation of less than .3 turn per inch, whereas packages of yarn produced on the prior twisting and winding devices have the variation of from .4 to .6 turn per inch.

It is to be understood that the foregoing detailed description and drawing is given merely 40 by way of illustration and that many variations may be made therein without departing from the spirit of our invention.

Having described our invention, what we desire to secure by Letters Patent is:

- 45 1. Apparatus for winding textile packages, comprising a spindle for holding and rotating a package to be wound, variable-speed driving means for rotating said spindle, control means in connection with said driving means for varying the speed of said spindle, and a positive driving connection between said spindle and said control means whereby said speed is held in predetermined relation to the number of revolutions already executed by said spindle in the winding of said package.
- 50 2. Apparatus for winding textile packages, comprising a spindle for holding and rotating a package to be wound, variable-speed driving means for rotating said spindle, control means in connection with said driving means for varying the speed of said spindle, a positive driving connection between said spindle and said control means whereby said speed is held in predetermined relation to the number of revolutions already executed by said spindle in the winding of said package, and means independent of the drive to said spindle for driving said control means in the interval between the winding of successive packages in a direction opposite to that in which it is driven by said positive driving connection so as to adjust said variable-speed driving means to give the requisite speed to the spindle at the beginning of the winding of the next package.
- 55 3. Apparatus for winding textile packages,

comprising a spindle for holding and rotating a package to be wound, variable-speed driving means for rotating said spindle, control means in connection with said driving means for varying the speed of said spindle, a positive driving connection between said spindle and said control means whereby said speed is held in predetermined relation to the number of revolutions already executed by said spindle in the winding of said package, and means independent of the drive to said spindle for driving said control means in the interval between the winding of successive packages, first for a certain amount in the opposite direction to, and then for a smaller amount in the same direction as it is driven by said positive driving connection so as to adjust said variable-speed driving means to give the requisite speed to the spindle at the beginning of the winding of the next package and to take up any backlash in said control means.

4. Apparatus for winding textile packages, comprising a spindle for holding and rotating a package to be wound, variable-speed driving means for rotating said spindle, control means in connection with said driving means for varying the speed of said spindle, a positive driving connection between said spindle and said control means whereby said speed is held in predetermined relation to the number of revolutions already executed by said spindle in the winding of said package, and a reversible motor adapted to be used alternately with said positive driving connection for driving said control means in the interval between the winding of successive packages, first for a certain amount in the opposite direction to, and then for a smaller amount in the same direction as it is driven by said positive driving connection so as to adjust said variable-speed driving means to give the requisite speed to the spindle at the beginning of the winding of the next package and to take up any backlash in said control means.

5. Apparatus for winding textile packages, comprising a spindle for holding and rotating a package to be wound, variable-speed driving means for rotating said spindle, control means in connection with said driving means for varying the speed of said spindle, a positive driving connection between said spindle and said control means whereby said speed is held in predetermined relation to the number of revolutions already executed by said spindle in the winding of said package, a reversible motor adapted to be used alternately with said positive driving connection for driving said control means and automatic means, controlled by the position of said control means for stopping the rotation of said spindle when it has reached a predetermined speed and simultaneously changing said control means from said positive driving connection to said reversible motor, for reversing said reversible motor after it has driven said control means beyond the position required for beginning the winding of the next package, and for stopping the said reversible motor when it has again reached said position.

6. Apparatus for winding textile packages, comprising a spindle for holding and rotating the package to be wound and means for rotating said spindle at a varying speed, said means including a variable speed transmission having a constant speed shaft, a variable speed shaft and a control shaft for controlling the speed of said variable speed shaft, a reversible motor for operating said control shaft to change the speed of

said variable speed shaft and means comprising a pivotally mounted gear train for connecting said reversible motor to and disconnecting the same from said control shaft.

5 7. Apparatus for winding textile packages, comprising a spindle for holding and rotating the package to be wound and means for rotating said spindle at a varying speed, said means including a variable speed transmission having a constant speed shaft, a variable speed shaft and a control shaft for controlling the speed of said variable speed shaft, a spur gear mounted on said control shaft, a reversible motor for operating said control shaft to change the speed of said variable speed shaft, a pivotally mounted train of gears connecting said reversible motor and said spur gear and means for moving said train of gears into and out of mesh with said spur gear.

20 8. Apparatus for winding textile packages, comprising a spindle for holding and rotating the package to be wound and means for rotating said spindle at a varying speed, said means including a variable speed transmission having a constant speed shaft, a variable speed shaft and a control shaft for controlling the speed of said variable speed shaft, a spur gear mounted on said control shaft, a reversible motor for operating said control shaft to change the speed of said variable speed shaft, a pivotally mounted train of gears connecting said reversible motor and said spur gear, and means comprising, solenoids and limit switches for controlling said solenoids, for moving said train of gears into and out of mesh with said spur gear.

25 9. Apparatus for winding textile packages comprising a spindle for holding and rotating the package to be wound and means for rotating said spindle at a varying speed, said means including a variable speed transmission having a constant speed shaft, a variable speed shaft and a control shaft for controlling the speed of said variable speed shaft, a speed reducer and a reversible motor connected to said control shaft for changing the speed of said variable speed shaft and means for disconnecting said reversible motor from said control shaft and for operatively connecting said speed reducer thereto.

40 10. Apparatus for winding textile packages, comprising a spindle for holding and rotating the package to be wound and means for rotating said spindle at a varying speed, said means including a variable speed transmission having a constant speed shaft, a variable speed shaft and a control shaft for controlling the speed of said variable speed shaft, a speed reducer and a reversible motor connected to said control shaft for changing the speed of said variable speed shaft and means for disconnecting said reversible motor from said control shaft and for operatively connecting said speed reducer thereto, said disconnecting means comprising a 2-way clutch mounted on said control shaft.

45 11. Apparatus for winding textile packages, comprising a spindle for holding and rotating the package to be wound, a variable speed transmission for rotating said spindle at a varying speed, said variable speed transmission having a driven constant speed shaft, a variable speed shaft for driving said spindle and a control shaft for controlling the speed of the variable speed shaft, a 2-way clutch attached to said control shaft, a speed reducer and a reversible motor connected to said control shaft for rotating the same to change the output speed of said variable

speed shaft, means for disconnecting said reversible motor from said 2-way clutch whereby said speed reducer operates said control shaft to reduce the speed of said variable speed shaft at a predetermined varying rate.

12. Apparatus for winding textile packages, comprising a spindle for holding and rotating the package to be wound, a variable speed transmission for rotating said spindle at a varying speed, said variable speed transmission having a driven constant speed shaft, a variable speed shaft for driving said spindle and a control shaft for controlling the speed of the variable speed shaft, a 2-way clutch attached to said control shaft, a speed reducer and a reversible motor connected to said control shaft for rotating the same to change the output speed of said variable speed shaft, means including solenoids and limit switches for operating the same, means for disconnecting said reversible motor from said 2-way clutch whereby said speed reducer operates said control shaft to reduce the speed of said variable speed shaft at a predetermined varying rate.

13. Apparatus for winding textile packages, comprising a spindle for holding and rotating the package to be wound, a variable speed transmission for rotating said spindle at a varying speed, said variable speed transmission having a driven constant speed shaft, a variable speed shaft for driving said spindle and a control shaft for controlling the speed of the variable speed shaft, a 2-way clutch attached to said control shaft, a speed reducer and a reversible motor connected to said control shaft for rotating the same to change the output speed of said variable speed shaft, means for disconnecting said reversible motor from said 2-way clutch whereby said speed reducer operates said control shaft to reduce the speed of said variable speed shaft at a predetermined rate and means for stopping the rotation of said spindle when the speed thereof has reached a predetermined rate.
